BUNTER FOR WEFT REPLENISHING LOOMS

Gabriel C. Beatrice, Shrewsbury, Mass., assignor to Crompton & Knowles Loom Works, Worcester, Mass., a corporation of Massachusetts

Application December 14, 1950, Serial No. 200,834

3 Claims. (Cl. 139—243)

1

This invention relates to improvements in weft replenishing looms and it is the general object of the invention to provide a transerrer mechanism operating bunter which when worn at one point along its length can be reversed to present a new operating part thereof for cooperation with the transferring mechanism.

Weft replenishing mechanisms of the bobbin changing type ordinarily employ a bobbin transerrer arm having a latch for cooperation with a bunter on the loom lay. The latch is normally in an inoperative position but is moved into position for cooperation with the lay bunter preparatory to a replenishing or bobbin changing operation. The bunter is frequently made as an integral part of the structure of the shuttle box at the replenishing end of the loom and when worn requires replacement of the box plate.

It is an important object of the present invention to make the bunter separate from the shuttle box structure and of such form that when one end of it becomes worn the bunter can be reversed to move its other unused end into position for cooperation with the transerrer arm latch.

When the replenishing mechanism is set for transfer, the transerrer latch is generally lifted so that a notch in it is at a given position or elevation favorable for cooperation with the bunter and the latter is made with a pointed or wedge-like front edge located at said position to enter the notch. It is a further object of the invention to provide a bunter having the operating edge thereof and the attaching means for the bunter so related that when the bunter is reversed its operating edge will be at the previous given elevation or position for correct cooperation with the transerrer latch.

It is a further object of the invention to provide some part of the lay structure, such as the plate of a shuttle box, with a vertical surface for engagement with a similar surface on the back of the bunter and provide securing means such as screws to be tapped into the lay structure, the holes for the screws in both the bunter and the lay box plate being so related to the operating front edge of the bunter that when the latter is reversed and the screws are replaced the operating edge of the bunter will be at its original level.

With these and other objects in view which will appear as the description proceeds, the invention resides in the combination and arrangement of parts hereinafter described and set forth.

2

In the accompanying drawings, wherein a convenient embodiment of the invention is set forth:

Fig. 1 is a side elevation of part of a weft replenishing mechanism having the invention applied thereto, the lay, shuttle box and shuttle being shown in cross section.

Fig. 2 is an enlarged plan view looking in the direction of arrow 2, Fig. 1.

Figs. 3 and 4 are enlarged vertical sections on lines 3—3 and 4—4, respectively, Fig. 2.

Fig. 5 is a perspective view of the bunter.

Fig. 6 is a diagrammatic plan view showing the bunter in its original position but having the part thereof for cooperation with the transerrer latch worn to such an extent as to require reversal of the bunter, and

Fig. 7 is a view similar to Fig. 6 showing the bunter after it has been reversed.

Referring to Fig. 1, a loom frame 1 supports a stand 2 on which a reserve bobbin magazine M is mounted for angular motion about a stud 3 fixed with respect to the stand 2. The magazine has front and back stacks of reserve bobbins B1 and B2 for replenishment of either of two shuttles with which the loom operates. The stand 2 has a horizontal stud 4 on which is pivoted a transerrer arm 5 the lower part of which has a latch holder 6 pivoted thereto as at 7. A transerrer latch 8 is secured to the holder 6 and is normally in the down position shown in Fig. 1. Mechanism is generally provided for lifting the latch preparatory to a weft replenishing operation of the loom, this lifting being effected as for instance by the rod 9 which can be raised by known means to lift the latch so that a notch 10 in it will be at a given elevation or position to receive the bunter designated herein generally at B.

The loom lay L is reciprocated backwardly and forwardly in usual manner and includes a beam 11 the upper part of which is provided with a shuttle box designated generally at 12. This box in the present instance has a front wall 13 secured to a plate 14 fixed with respect to the lay by means of screw 15. The usual binder 16 is in the present instance located at the back of the shuttle box. The plate 14 may conveniently be the shuttle box plate of the lay and has a forward extension 17 shown more particularly in Fig. 2.

At the time of a replenishing operation the lowest bobbin in one or the other of the stacks B1 or B2 will be in transfer position and the bunter will move forwardly with the lay, to the left in Fig. 1, and engage the raised latch to

3

rock the transerrer arm 5 in a clockwise direction, Fig. 1, to push the bobbin in transfer position into the shuttle S which in the present instance is assumed to be the shuttle corresponding to the front stack of bobbins B1.

The matter thus far described is of common construction and except as noted hereinafter forms no part of the present invention. The magazine M is set forth merely for illustrative purposes and it is to be understood that the invention is not necessarily limited in its use to this type of magazine.

The shuttle box plate extension 17 is provided with a vertical flat surface 20 which extends lengthwise of the shuttle box and preferably though not necessarily parallel to the axis of the shuttle box. The extension 17 is provided with two tapped holes 21 and 22 to receive the screw threads of screws 23 and 24, respectively. The bunter B is made preferably of a single piece of metal and has an elongated body 30 the ends of which have extended therethrough horizontal holes 31 and 32 to receive the screws 23 and 24, respectively. The body 30 has a rear flat vertical surface 33 to fit the surface 20 of the shuttle box plate. Extending forwardly from the body 30 is a part 35 of the bunter which has direct engagement with the latch 8. This part 35 is made wedge shaped with upper and lower inclined surfaces 36 and 37, respectively, which meet at an operating edge 38 which is preferably parallel to the rear surface 33. The part 35 extends between the ends 39 and 40 of the bunter and the surfaces 36 and 37 are so related with respect to the bunter that the edge 38 is preferably in a plane perpendicular to the rear surface 33 and passing centrally through the holes 31 and 32. The edge 38 and the centers of holes 21, 22 and 31, 32 are at substantially the same level with respect to the plane of the box plate 14.

In the original assembly of the bunter it will be attached to the shuttle box plate 14 as shown in Fig. 6 with the screws 23 and 24 passing through their respective holes 31 and 32 and tapped into their respective holes 21 and 22 in the box plate to hold the latch operating edge 38 at a given elevation with respect to the lay or box plate and with one end only of the edge 38 in position for engagement with the latch 8. Successive weft replenishing operations of the loom will cause cooperation between the left end of edge 38 as viewed in Fig. 6 and the latch 8 and said left end of the edge will eventually become worn, as indicated at W.

When this condition arises the screws 23 and 24 are removed and the bunter is reversed end for end so that the unused end of edge 38 which previously was adjacent to tapped hole 21 will now be adjacent to tapped hole 22 and end 40 will be adjacent to hole 21. The screws are then replaced to hold the rear surface 33 firmly against the surface 20 of the shuttle box plate. In this new setting the worn part W of the bunter will be at one side of the latch 8 and the latter will be engaged by the fresh or unused part of the edge 38, as indicated in Fig. 7. Because of the fact that the edge 38 is at the same level as the tapped holes 21 and 22 and the clear holes 31 and 32 the reversal of the bunter will locate the fresh unworn part of the edge 38 at the same elevation which it originally had so that it can cooperate properly with the transfer latch 8.

From the foregoing it will be seen that the invention sets forth a simple form of reversible bunter for the latch of a bobbin transferring

4

mechanism. The bunter is applied directly to the front face 20 of the box plate 14 by attaching means such as the screws 23 and 24 which are at substantially the same elevation as the operating edge 38 so that when the bunter is reversed as described in connection with Figs. 6 and 7 the operating edge 38 will be in its original given position or elevation. This reversal is made possible by the fact that the bunter edge 38 is sufficiently long so that only one end of it at a time cooperates with the latch 8, and when this end becomes worn the bunter can become reversed end for end to present a fresh and previously unused part of the edge 38 for cooperation with the latch.

Having thus described the invention it will be seen that changes and modifications of the foregoing specific disclosure may be made without departing from the spirit and scope of the invention.

What is claimed as new is:

1. In a weft replenishing loom having a transerrer latch and a shuttle box having a horizontal box plate formed with a flat vertical surface on the front thereof extending lengthwise of the shuttle box, a bunter member for the latch formed with an elongated body provided with a flat surface on the back thereof abutting the flat vertical surface of said box plate, said member having a forwardly extending wedge shaped latch engaging part formed with an edge extending lengthwise of and parallel to said body, and means securing the ends of said body to said plate with one end only of the wedge shaped part in position to engage said latch, said bunter being reversible end for end and said means subsequent to said reversal being capable of securing the member to the box plate with the other end only of said wedge shaped part in position to engage said latch.

2. In a weft replenishing loom having a bobbin transerrer arm latch and a horizontal shuttle box plate formed with a flat front vertical surface extending lengthwise of a shuttle box rearward of the latch, a bunter member for said latch formed with an elongated horizontal body having a flat vertical rear surface abutting said surface on the box plate and having a wedge shaped part extending forwardly from said body, said wedge shaped part having a horizontal forward edge to engage the latch, and screws extending through said body, one screw for each end of said body, said screws being tapped into said box plate to hold the bunter member to said box plate with one end only of said edge in position to engage said latch, said screws being at the same level as said edge and holding said member with said edge at a given elevation, and said member being reversible end for end and said screws subsequent to said reversal of the member being effective to hold the latter with the other end only of the edge thereof in position to engage the latch and with said edge at said given elevation.

3. In a weft replenishing loom having a bobbin transerrer arm latch and a horizontal shuttle box plate formed with a flat front vertical surface extending lengthwise of a shuttle box rearward of the latch, a bunter member for said latch formed with an elongated horizontal body having a flat vertical rear surface abutting said surface on the box plate and having a wedge shaped part extending forwardly from said body, said wedge shaped part having a horizontal forward edge to engage the latch at a given elevation, and 75 securing means extending through said body into

said box plate at said given elevation and holding the member to said box plate with one end only of said edge in position to engage said latch at said elevation, said member upon removal of said securing means being reversible end for end and said securing means when replaced subsequent to said reversal of the member holding the latter with the other end only of said edge in position to engage said latch at said given elevation.
